UNITED STATES PATENT OFFICE.

CLARENCE H. HOWARD, OF ST. LOUIS, MISSOURI.

CAR-UNDERFRAME.

No. 922,586.

Specification of Letters Patent.

Patented May 25, 1909.

Application filed November 23, 1908. Serial No. 484,036.

To all whom it may concern:

Be it known that I, CLARENCE H. HOWARD, a citizen of the United States, residing at St. Louis, in the State of Missouri, have invented a new and useful Improvement in Car-Underframes, of which the following is a specification.

My invention relates to a cast metal underframe particularly adapted for a railroad self-cleaning dump-car, such as an ore, gondola, or analogous car, and has for its object to provide a strong, rigid and durable underframe adapted to form a bottom end support for the upright and diagonal side members of the car body and thereby transmit the vertical stress of the load therethrough uniformly to entire underframe.

The invention consists in features of novelty as hereinafter described and claimed, reference being had to the accompanying drawing forming part of this specification, whereon,

Figure 1, is a top plan view of my improved cast metal underframe adapted for a self-clearing ore dump-car, omitting the car body; Fig. 2, a side elevation thereof showing the car body thereon broken away; Fig. 3, a vertical longitudinal section through the underframe on line 3, 3, in Fig. 1, and corresponding section through the car body; Fig. 4, a vertical transverse section through the underframe and car body on line 4, 4, in Fig. 3, and Figs. 5 and 6, detail views of part of the underframe as seen respectively, in Figs. 3 and 4, showing an alternative construction of the said part.

Like letters and numerals of reference denote like parts in all the figures.

a represents my improved car underframe which is composed preferably of cast steel integral throughout and may be of any suitable design as to the number, arrangement, and cross section of its component members, comprising preferably, in the present case, two opposite channel longitudinal side members 1, a channel member or end sill 2 uniting the side members 1 together at their respective ends and having its middle portion preferably, box-shaped and adapted thereto to increase the resistance of the underframe *a* to end shocks, two opposite longitudinal channel members 3 at a suitable distance apart and intermediate to the side members 1, and united at each end to the corresponding end sill 2, a transverse preferably I-shaped member 4 adjacent to each end sill 2, intersecting

the intermediate longitudinal members 3 and united at each end to the corresponding side member 1, the transverse members 4, which with the longitudinal members 3 form the opening *b* through the middle and adjacent part of the underframe *a* for receiving the lower portion of the hopper *c* of the car body as hereinafter more particularly referred to, constituting the body-bolsters and adapted for the application thereto of a suitable draft-gear, such as *d* as seen to the left in Figs. 1 and 3, and the members 3 and 4 having preferably, on their inner or opposite sides, gussets 5 at their junction with each other, the members 1 and 3 being united together respectively, at a suitable distance from the center of the underframe *a* by transverse channel members 6, and the longitudinal members 3 united to each other at the middle by a preferably, L-shaped transverse bar 7 having its apex alined to the transverse center of the underframe *a* and its flanges respectively inclined downward on each side of the said center at an angle of 45°, the bar 7 having, on the inner side of each flange, lugs 8 to which the drop-doors *e* of the hopper *c* are hinged as seen in Fig. 3.

Projecting from the outside of each side member 1 and integral therewith are formed a series of horizontal brackets 9 which are adapted to support, and on which the bottom ends of the upright posts *f* of the car body bear, the posts *f* being respectively, guided or maintained in a vertical position by lateral upright webs 9' which are integral with the brackets 9 and side members 1, while from the outside of the webs 9' along the side members 1 and integral therewith, project horizontal brackets 10 which are adapted to support and bear against the bottom ends of the diagonal braces *g* of the car body, the brackets 10 being arranged respectively, on one or both sides of the brackets 9 with their lateral upright webs 9', according to the disposition of the diagonal braces *g* as shown in Figs. 1 and 2, and the brackets 9, webs 9', and brackets 10 having suitable outside strengthening ribs 11 integral therewith and with the side members 1 substantially as shown. Furthermore, on the underframe *a* at the junction of the end sills 2 and intermediate longitudinal members 3, are formed upwardly projecting pockets 12 for receiving the bottom ends of the upright end posts *f'* (Fig. 3) of the car body, and on the side and intermediate longitudinal mem-

bers 1 and 3 adjacent to the pockets 12, are formed pockets 13 which are integral with the said members and adapted to receive the bottom ends of the end diagonal braces g' .

From the underside of, and preferably integral with each intermediate longitudinal member 3 adjacent to the bottom outlet 14 from the hopper c at each side of, and equidistant from the transverse center line of the underframe a , depends a suitably shaped bracket 15 from which projects laterally a pocket 16 beneath the opening b , the pocket 16 being adapted to receive and hold the corresponding end of a bar h which forms the bottom transverse sill of the inclined end wall 17 of the hopper c , and against which the drop-door e is closed as seen in Figs. 2 and 3. Or if desired the bracket 15 with the pocket 16 in lieu of being integral with the underframe a as described, may be of separate construction and fixed thereto by rivets 18, or otherwise, as shown in Figs. 5 and 6.

In the above construction of underframe, by supporting the upright posts f and diagonal braces g endwise upon the brackets 9 and 10, which are integral with the underframe a , the vertical stress of the load within the hopper c upon the said posts and braces is transmitted therethrough directly to and uniformly through the entire underframe; moreover, by uniting the ends of the hinge-bar 7 for the drop-doors of the hopper c to the intermediate longitudinal members 3 of the underframe a the latter is greatly strengthened at its middle or weakest part and its resistance thereto to the lateral stress of the load increased, and furthermore, by fixing the bottom outlet sill h of the hopper c in pockets having their walls integral with the underframe, the hopper c is greatly strengthened and rendered more durable thereto, and positive closing of the drop-doors e insured at all times.

What I claim as my invention and desire to secure by Letters Patent is:

1. In a car underframe of the character described, a bracket projecting outwardly from and integral with a side member of the said frame and adapted at the top to form a bearing for the bottom end of an upright post of the car body, substantially as described.

2. In a car underframe of the character described, a bracket projecting outwardly from and integral with a side member of the said frame and adapted at the top to form a bearing for the bottom end of an upright post of the car body, and two opposite webs integral with the said member and adapted to bear against the transverse sides of the said post in its assembled position on the said bracket, substantially as described.

3. In a car underframe of the character described, a bracket projecting outwardly

from a side member of the said frame and adapted at the top to form a bearing for the bottom end of an upright post of the car body, two opposite webs projecting from the said member and adapted to bear against the transverse sides of the said post in its assembled position on the said bracket, and a bracket projecting from the said member and adapted at the top to form a bearing for the bottom end of a diagonal brace of the car body, the said brackets and webs being integral with the said frame, substantially as described.

4. In a car underframe of the character described, a pocket formed on and integral with the said frame, the said pocket being closed on all sides except the top and front for the lateral insertion therein of the bottom end portion of an upright post of the car-body, substantially as described.

5. In a car underframe of the character described, a pocket formed on and integral with the said frame, and adapted to receive the bottom end of a diagonal brace of the car body, substantially as described.

6. In a car underframe of the character described, a bracket dependent from and integral with the said frame and having a lateral pocket adapted to receive and hold the corresponding end of a transverse member of a hopper at its outlet end, substantially as described.

7. In a car underframe of the character described, a bracket dependent from the said frame and having a lateral pocket adapted to receive and hold the corresponding end of a transverse member of a hopper at its outlet end, substantially as described.

8. In a car underframe of the character described, a transverse bar spanning and integral with the walls of, the middle opening through the said frame, and adapted for pivoting the drop door of a hopper thereto, substantially as described.

9. In a car underframe of the character described, the combination of the side members, the end sills, transverse members uniting the side members together and adapted for the application thereto of a suitable draft-gear, brackets projecting outwardly from the side members and adapted to form bearings for the bottom end of the upright posts of the car body, webs projecting from the side members and adapted to bear against the transverse sides of the said posts, and brackets projecting from the side members and adapted at the top to form bearings for the bottom ends of the diagonal braces of the car body, all the said parts being integral throughout, substantially as described.

10. In a car underframe of the character described, the combination of the side members, the end sills, transverse members uniting the side members together and adapted for the application thereto of a suitable dr.

gear, a bracket dependent from the said frame and having a lateral pocket adapted to receive and hold the corresponding end of a transverse member of a hopper at its outlet end, substantially as described.

11. In a car underframe of the character described, the combination of the side members, the end sills, transverse members uniting the side members together and adapted for the application thereto of a suitable draft-

gear, a transverse bar spanning and integral with the walls of, the middle opening through the said frame and adapted for pivoting the drop-door of a hopper thereto, substantially as described.
